CLAIM

The ornamental design for a vehicle ceiling console, as shown and described.

DESCRIPTION

FIG. 1 is a perspective view of a vehicle ceiling console in a closed position showing our new design; and,

FIG. 2 is a perspective view of a vehicle ceiling console in an open position thereof.

The broken line showings of the edges of inner compartment doors and the remainder of the vehicle interior depict environmental subject matter and form no part of the claimed design.

1 Claim, 2 Drawing Sheets

FIG. 2
